[57] ABSTRACT

A striker mechanism for a percussion igniter, which is particularly suitable for use with a pyrotechnic device, comprising a support adapted to receive a percussion igniter, a striker pivotally mounted on the support, spring means associated with the striker to urge the latter to rotate into a position in which it is driven against a percussion igniter mounted in the support, a cocking lever pivotally mounted on the support and engageable with the striker for the purpose of cocking the latter against the action of said spring means, and an actuating lever pivotally mounted on said support for moving said cocking lever in order first to cock the striker and then to release it to enable the spring means to re-assert itself and drive the striker towards said position.

STRIKER MECHANISMS FOR PERCUSSION IGNITERS

This invention relates to an improved striker mechanism for initiating a percussion igniter.

One known striker mechanism for initiating a percussion igniter comprises a cylindrical striker pin which is urged towards the igniter, in the axial direction of the pin, by a striker spring which surrounds the striker pin. The striker pin is held by a keeper plate in a cocked position in which the striker spring is compressed. When the keeper plate is removed, the striker spring re-asserts itself and drives the striker pin towards the percussion igniter to initiate the latter. Such a striker mechanism has the disadvantage that the striker spring is permanently stressed until the mechanism is actuated and this can lead to weakening of the spring with consequent risk of failure of the mechanism to initiate the igniter. Another disadvantage of this known mechanism is the risk of premature actuation of the mechanism if the keeper plate should become dislodged accidentally.

In order to overcome the above disadvantages, various proposals have been made to provide the above-described striker mechanism with means for cocking the striker pin immediately prior to actuation of the mechanism. These prior proposals, however, have been of a complicated nature and have added considerably to the cost of the striker mechanism.

An object of the present invention is to provide a striker mechanism for a percussion igniter which is of simple and cheap construction and which does not have the disadvantages of the previously known striker mechanism.

According to the invention, a striker mechanism for a percussion igniter comprises a support adapted to receive a percussion igniter, a striker pivotally mounted on the support, spring means associated with the striker to urge the latter to rotate into a position in which it is driven against a percussion igniter mounted in the support, a cocking lever pivotally mounted on the support and engageable with the striker for the purpose of cocking the latter against the action of said spring means, and an actuating lever pivotally mounted on said support for moving said cocking lever in order first to cock the striker and then to release it to enable the spring means to re-assert itself and drive the striker towards said position.

Preferably, said support is a cup-shaped body having a cylindrical wall and a closed end, a centrally disposed hole being provided in the closed end for the reception of a percussion igniter. Outwardly projecting lugs may be secured to, or formed integrally with, the end of the cup-shaped body for the purpose of supporting pins on which the various levers of the mechanism are pivotally mounted.

Preferably, the actuating lever can be pivoted into, and locked in, a position in which it rests against the striker and prevents pivoting movement of the latter in the cocking direction. The actuating lever may be locked in this position by means of a locking device, for example a split pin, removably mounted on the support.

The invention will now be described in greater detail, by way of example, with reference to the drawing, in which

FIGS. 1 to 3 are sectional elevation views of a striker mechanism in accordance with the invention, with the movable parts of the mechanism shown in different positions in the three Figures, and

5 FIG. 4 is a plan corresponding to FIG. 2.

Referring to the drawing, the striker mechanism illustrated comprises a cup-shaped body, made for example of plastics material, having a cylindrical wall 1 and a closed end 2. A central, axially disposed hole 3 in the end 2 has a counterbored portion 4 at its outwardly facing end, and a percussion igniter 5 is mounted in the hole 3 and the counterbored portion 4.

Two parallel, outwardly projecting, spaced-apart lugs 6 are formed integrally with the end 2, these lugs being disposed symmetrically with respect to the hole 3. The lugs 6 serve as supports for the ends of two pins 7, 8 which are parallel to one another and disposed in spaced parallel relationship to the end 2.

10 A striker plate 9 is pivotally mounted on the pin 7 between the lugs 6, this striker plate being provided with a firing pin 10. A coil spring 11 on the pin 7 urges the striker plate to turn in an anti-clockwise direction about the pin 7 to bring the firing pin 10 into engagement with the igniter 5.

15 A bent cocking lever 12 is pivotally mounted on the pin 8 between the lugs 6, this lever comprising joined portions 13 and 14 disposed substantially at right angles to one another. The portion 13 is pivotally mounted on the pin 8, whilst the portion 14 is forked at its end remote from the pin 8 to provide a pair of prongs 15.

20 A bent actuating lever 16 is also pivotally mounted on the pin 8 between the lugs 6, this actuating lever comprising joined portions 17 and 18 disposed substantially at right angles to one another, the portion 17 being pivotally mounted on the pin 8.

25 FIG. 1 shows the striker mechanism in its uncocked position, in which the prongs 15 of the cocking lever 12 are disposed between the striker plate 9 and the end 2 to prevent the firing pin 10 engaging the igniter 5. The actuating lever 16 is folded over into a position where its portion 18 rests on the striker plate 9. The actuating lever may be retained in this position by a split pin (not shown) passing through axially aligned holes 19 in the lugs 6. In this condition of the mechanism the spring 11 is only lightly stressed and merely holds the striker plate 9 lightly against the prongs 15 of the cocking lever.

30 To initiate the igniter 5, the actuating lever 16 is swung in the direction of the arrow A (FIG. 1) until its portion 17 bears against the portion 13 of the cocking lever. Continued rotation of the actuating lever in the same direction about the pin 8 causes the cocking lever 12 to rotate in the direction of the arrow B (FIG. 2), with the result that the prongs 15 cause the striker plate 19 to pivot in the direction of the arrow C about the pin 7. This rotation of the striker plate 9 stresses the spring 11.

35 Continued rotation of the actuating lever in the direction of the arrow A results in the prongs 15 moving free of the striker plate 9, with the result that the spring 11 can then re-assert itself and rotate the striker plate 9 rapidly in the direction opposite to the arrow C, so that the firing pin 10 is driven into the igniter (FIG. 3).

In the Figures the striker mechanism is shown mounted in, and closing, the end of a tubular casing 20, which may be the casing of a pyrotechnic device. A removable protective cap 21 (shown in outline by a chain line in FIG. 1 only) may be secured over the striker mechanism to prevent the ingress of moisture.

From the above description it will be appreciated that the striker mechanism illustrated in the drawing is of a very simple construction, that the spring 11 is not weakened during storage of the mechanism and that there is virtually no risk of the mechanism being actuated accidentally when it is in the condition shown in FIG. 1.

What is claimed is:

1. A mechanism for initiating a percussion igniter comprising:
 a support adapted to receive a percussion igniter, means mounted on the support for initiating the percussion igniter, spring means associated with the initiating means to urge the latter against a percussion igniter mounted in the support, a cocking lever pivotally mounted on the support and engageable with the initiating means for the purpose of cocking the latter against the action of said spring means, an actuating lever pivotally mounted on said support, the actuating lever having means for engaging the cocking lever so that the actuating lever as it moves about its pivot point first engages and moves the cocking lever together with the initiating means against said spring means to an armed position and second, moves the cocking lever out of engagement with the initiating means thereby releasing the initiating means to be driven against

the percussion igniter under the force of said spring means, said actuating lever being configured to lie in nested relation when pivoted to a position adjacent said initiating means and said cocking lever for storage prior to use.

5 2. A mechanism according to claim 1, in which said support is a cup-shaped body having a cylindrical wall and a closed end, a centrally disposed hole being provided in the closed end for the reception of a percussion igniter.

10 3. A mechanism according to claim 2, in which outwardly-projecting lugs are secured to, the end of the cup-shaped body for the purpose of supporting a pin on 15 which the striker is mounted.

4. A mechanism according to claim 3, in which said lugs support a further pin on which the cocking lever and the actuating lever are mounted.

20 5. A mechanism according to claim 1, in which the actuating lever can be pivoted into, and locked in, a position in which it rests against the initiating means and prevents pivoting movement of the latter in the cocking direction.

25 6. A mechanism according to claim 1, comprising a removable protective cap secured to said support to prevent the ingress of moisture to a percussion igniter mounted in the support.

30 7. A mechanism according to claim 1, in which the initiating means comprises a striker pivotally mounted on the support and adapted for direct striking contact with the percussion igniter.

35 8. A mechanism according to claim 1, in which each of the cocking lever and the actuating lever includes shoulder means through which the actuating lever rotates the cocking lever.
